UNITED STATES PATENT OFFICE

EDWARD B. MOSSER, OF PHILADELPHIA, PENNSYLVANIA, ASSIGNOR TO LEHIGH SILK
HOSIERY MILLS, INC., OF NEW YORK, N. Y., A CORPORATION OF NEW YORK

DESIGN FOR A STOCKING

Application filed January 16, 1932. Serial No. 42,503. Term of patent 3½ years.

To all whom it may concern:

Be it known that I, EDWARD B. MOSSER, a citizen of the United States, residing at Philadelphia, in the county of Philadelphia and State of Pennsylvania, have invented a new, original, and ornamental Design for a Stocking, of which the following is a specification, reference being had to the accompanying drawing, forming part thereof.

Figure 1 is a side elevation of a stocking;
Fig. 2 is a detail view of the fabric consti-

tuting the leg portion of the stocking illustrated in Fig. 1. In this view (Fig. 2) the fabric is shown enlarged approximately 1½ times actual size, but which in the reduction to patent size will show the fabric approximately actual size.

I claim:

The ornamental design for a stocking, as shown and described.

EDWARD B. MOSSER.
